UNITED STATES PATENT OFFICE.

FRANCIS O. BLACKWELL, OF NEW YORK, N. Y., ASSIGNOR TO THE THOMSON-HOUSTON ELECTRIC COMPANY, OF CONNECTICUT.

ELECTRIC-RAILWAY CONTACT.

SPECIFICATION forming part of Letters Patent No. 425,489, dated April 15, 1890.

Application filed August 31, 1889. Serial No. 322,633. (No model.)

To all whom it may concern:

Be it known that I, FRANCIS O. BLACKWELL, a citizen of the United States, residing at New York, in the county of New York and State of New York, have invented certain new and useful Improvements in Electric-Railway Contacts, of which the following is a specification.

My invention relates to contact devices for an overhead electric railway.

In the contact devices heretofore employed it has been customary to make substantially the whole of the device between the car and the wire movable laterally in order to accommodate it to the sinuosities of the line. It has been also customary in these devices to make the contact device have a lateral movement about a center instead of in a straight line, so that there was a constant tendency to throw the contact-wheel off the wire on account of the deviations in the parallelism between the rod of the device and the wire.

My invention consists in providing an upright structure on the roof of the car and pivoting a contact device thereon which is comparatively light and easy to move laterally, and arranging it at the same time so that its lateral movement is not a movement about a center, but a movement directly across the car. The contact-rod is held up against the wire by means of a spring which does not offer any substantial interference with the lateral movement of the contact device.

Referring to the accompanying drawings, Figure 1 is a side elevation of my contact device. Fig. 2 is an end elevation thereof, and Fig. 3 is a modified detail.

In the drawings, A represents a vehicle— for example, a street-car.

B is the line-wire.

An intermediate contact device is formed by providing a rigid upright structure or standard on the roof of the car, consisting of two posts C and a cross-piece D. This cross-piece D is preferably round and is embraced by a traveler E, having an upward extension forming the trolley-rod, the trolley-wheel being carried on its outer extremity and riding along on the under side of wire B. The trav-

eler E has an offset G at an angle to F, and from its extremity a cord or wire H for manually moving the contact device into and out of its operative position extends to one end of the vehicle, where it is provided with a strong spring K and a handle L. The handle L has two trunnions adapted to fit in hooks or equivalent catches M for holding spring K under tension, which are attached at the end of the hood over the car-platform.

It will be readily seen that in operation the contact-trolley on the end of rod F will be constantly pressed up against wire B by the tension of spring K. The traveler E, carrying rod F, will be free to slide on guide D, and the point of attachment of spring K is so remote that it will not offer any substantial obstacle to the free transverse movement of E. The rod F may be easily manipulated by means of handle L, and, if desired, there may be two extensions G on traveler E, and two wires H may extend directly down around the transversely-sliding pulley O, whence the wire H extends to the end of the car and is provided with a spring K, as in the previous arrangement. This modification is illustrated in Fig. 3.

What I claim as new, and desire to secure by Letters Patent, is—

1. The combination, with a railway-vehicle and a line-wire, of a standard fixed on the top of the vehicle and a light transversely-sliding contact-piece upon said standard pressed constantly against the under side of the supply-wire.

2. The combination, with an electric-railway vehicle and a line-conductor, of an intermediate contact device consisting of a standard and a contact-arm thereon pressed against the supply-wire and movable on said standard in substantially a straight line.

3. The combination, with an electric-railway vehicle, of an intermediate contact device consisting of a standard, a transversely-moving trolley-rod thereon, and a spring pressing the said rod against the line-conductor without obstructing the transverse movement.

4. The combination, with an electrically-propelled vehicle and a stationary conductor, of an intermediate contact device consisting

of an upright standard, a trolley-rod thereon having freedom of movement in a straight line, and a spring pressing the said trolley against the line-wire and partaking of the 5 transverse movement.

5. The combination, with an electrically-propelled vehicle, of a suspended line-conductor and an intermediate contact device consisting of an upright standard, a pivoted 10 trolley-rod free to travel transversely therealong, and a controlling-connection provided with a spring extending to the end of the vehicle.

6. The combination, in an electrically-propelled vehicle and a suspended line-conductor, 15 of an intermediate contact device consisting of a standard having at its upper end a transverse guide and a pivoted trolley-rod sliding transversely on said guide and provided with 20 a spring pressing it against the main supply-wire.

7. The combination, in an electrically-propelled vehicle, of a transverse guide allowing 25 freedom of lateral movement to the contact device and a contact-arm pivoted upon said

guide and swinging into and out of an operative position around it as a center.

8. The combination, with a pivoted trolley-rod F, of an operating-connection H, provided with a spring for manually controlling the 30 position of the contact device and extending to the end of the vehicle, and having there a hook or similar detachable connection.

9. The combination, in an electrically-propelled vehicle, with a contact device movable 35 into and out of operative position relatively to the conductor, of an operating-connection therefor comprising a spring portion and a hook or equivalent catch for securing the said connection when the contact device is moved 40 into operative position, whereby the spring will be put under tension to maintain the traveling engagement between the contact device and conductor.

Signed and witnessed this 20th day of Au- 45 gust, 1889.

FRANCIS O. BLACKWELL.
